AUTOMATIC TRAIN-PIPE COUPLING.

1,161,372.

Specification of Letters Patent. Patented Nov. 23, 1915.

Application filed April 22, 1915. Serial No. 23,235.

To all whom it may concern:

Be it known that I, MARTIN ALLEN BARBER, a citizen of the United States of America, and resident of the city of Montreal, Province of Quebec, Canada, have invented certain new and useful Improvements in Automatic Train-Pipe Couplings; and I do hereby declare that the following is a full, clear, and exact description of the same.

10 This invention relates to devices for the automatic coupling of the signal, brake and steam pipes of railway cars and has for an object to improve the general construction of automatic train pipe couplers.

15 The above with further objects and advantages will be hereinafter more fully described and particularly pointed out in the appended claims.

For full comprehension, however, of my invention reference should be had to the accompanying drawings forming a part of this specification, in which similar reference characters indicate the same parts and wherein:

25 Figure 1 is a side elevation of my improved coupler; Fig. 2 is a face view of same; Fig. 3 is a vertical section on line 3—3 Fig. 1; Fig. 4 is a horizontal section taken as indicated by line 4—4 Fig. 1 and showing 30 the couplers of two adjacent cars before coupling; and Fig. 5 is a similar view after coupling. Fig. 6 is a horizontal section on line 6—6 Fig. 2.

Although my improved coupler may be suspended in any suitable manner from the car 2, the particular embodiment illustrated and herein described is especially adapted for suspension from the draw bar 3 of the draft rigging and inasmuch as the train pipe couplers at the ends of adjacent cars to be coupled include similar parts a description of one of the improved couplers will be sufficient to clearly explain the invention.

A bracket 4 is suspended from the draw bar 3 preferably by means of a supporting member 5 which is slotted at 6 in the longitudinal line of the car, the upper end of the bracket being bifurcated, having its arms 7 located at opposite sides of the support and carrying bolts 8 which pass through the slot. The upper end of the bracket is widened to accommodate more than one bolt so that the bracket will be held against turning or tilt-

ing, the bolts being supplemented in this action by lugs 9 upon the interior of arms 7 and which bear flat against the underside of the support. The bracket extends downwardly a suitable distance and has an aperture 10 therein for the reception of the inner end of the shank 11 of the coupler head 12. The aperture 10 and inner end of shank 11 are preferably of angular formation to prevent turning, while the aperture is of slightly larger extent than the end of the shank so that the latter may move loosely therethrough. The outer edge of aperture 10 is beveled at 13 to enable the shank to move either laterally or vertically for a purpose to be hereinafter explained.

The inner end of the shank 11 carries a compression sleeve nut which is interiorly screw-threaded to engage with a threaded portion of the shank, the sleeve 12^a being tapered outwardly from the head 12^b and screw-threaded at the smaller end to receive 75 a lock nut 12^c the head 12^b being adapted to bear flat against the inner side of bracket 4 and preferably equal in extent to the width of the latter to insure the maximum bearing surface for a purpose to be presently explained. The sleeve is longitudinally split at 12^d so that when the lock nut is screwed thereon it will be tightly compressed upon the shank 11.

For simplicity in construction, ease of manufacture and strength the coupler head proper is made in one piece with the shank and consists of bearing frame 12 having at one side a projecting inclined and preferably pyramidal guide 14 and at the other side an opening 15 of sufficient extent to receive the pyramidal guide of the coupling of another car, the coupler heads being of right and left formation.

The apertures for the train pipe connections are compactly located so as not to unduly project beyond the normal confines of the bearing frame and in the preferred arrangement the air brake pipe aperture 16 is centrally located with respect to the frame 10 and in direct axial alinement with shank 11, the outer portion of which or that part adjacent the frame being hollowed out at 17 to form an air conduit leading rearwardly from aperture 16 to a side opening 18 provided with a nipple 19 by means of which

the usual air hose 20 is attached, the opening 18 being sufficiently far back to avoid any contact between the air hose and the pyramidal guide entering opening 15 in the frame.

5 The steam and signal pipe apertures 21 and 22 respectively are disposed at opposite sides of and preferably in vertical alinement with the brake pipe aperture and have 10 rearwardly extending nipples 23 to which their respective hose pipes 24 and 25 are attached, the aperture 22 being disposed nearer the central one 16 than is aperture 21. Gaskets 25^a are located in the pipe 15 apertures so that when the coupling heads of two cars come together and their respective apertures register fluid-tight joints will be made and through passages for the fluids provided.

20 The top, bottom and outer sides of the pyramidal guide are apertured while the inner side is recessed at 27 about the side of aperture 16 and flanks same at top and bottom, the sides of the recess inclining to approximately the vertical center line of said aperture 16 at such points. The recess provides for the location of the central aperture 16 and should it happen that the coupler heads are not in proper relative position 25 when two couplers are brought together the inclined sides direct the pyramidal guides into their respective openings and by so doing prevent such guides from striking and damaging the pipe apertures.

30 As shown by Figs. 2 and 6 the wall of the recess is curved in conformity with the aperture and extends preferably perpendicularly to the frame 12 and outwardly from the latter and such aperture and in a line substantially parallel with the axial 35 line of the latter. Thus when another coupler is engaged, a guideway and snug accommodation is provided for the portion of the frame surrounding the aperture of the other frame as illustrated in dotted lines 40 Fig. 6.

45 The position of the brake pipe aperture 16 in the center of the bearing frame and in axial or longitudinal alinement with shank 50 11 reduces to a minimum any tendency of the high pressure fluid which passes through the central apertures when the coupler heads are together, to force the frames apart as, were such aperture disposed to one 55 side of the shank, the leverage secured would appreciably augment such tendency. It will be seen, by so constructing the coupler as to combine this feature with the advantage of the pyramidal guides without exposing the pipe apertures to damage by the latter, that a most efficient, compact and reliable coupler is produced.

60 At the rear of frame 12 and adjacent the top of shank 11 a pair of spaced lugs 28 65 are formed and between these lugs a bar 29

is pivoted, such bar inclining upwardly and outwardly from the shank and passing loosely through an opening 30 in bracket 4 above aperture 10 and preferably in vertical line therewith. Similar spaced lugs 31 are 70 formed below and adjacent shank 11 and have a bar 32 pivoted therebetween, the bar 32 inclining downwardly and outwardly from the shank and passing loosely through an opening 33 in the bracket 4 and below 75 aperture 10.

75 The inner end of each of the bars 29 and 32 carries and is in screw-threaded engagement with a sleeve nut 34 which is adapted to bear against the inner side of bracket 4, 80 the sleeve extension 35 passing loosely through the opening in the bracket and being outwardly tapered at 36 for a portion of its length from the head or nut 34 to accommodate lateral movement of the bar in 85 the opening. A rocker sleeve 37 loosely encircles shank 35 and is formed with an inner rounded end bearing against the outer side of bracket 4, both the sleeve and the lugs upon frame 12 being reduced to form shoulders 38, 38^a and centering bosses 39 for a coiled spring 40 which encircles the bar, bears at its ends against the shoulders 38 and 38^a and tends to force the coupler head 90 away from the bracket. 95

95 As the bars are inclined with relation to frame 12 and bracket 4 I have, in order to provide bearing surfaces thereon perpendicular to the axial line of the springs, inclined the shoulders 38 of the spaced lugs 100 outwardly and forwardly with relation to shank 11, thus forming flat bearing surfaces for the outer ends of the springs. Inclined bearing bosses 41 are also formed upon the back and front of bracket 4 and 105 surround the upper opening 30 therein to form flat bearing surfaces for the nut 34 and rocker sleeve 37 of the upper bar 29. The perpendicular bearing surfaces for the nut and rocker sleeve of the lower bar 32 110 are presented by forwardly offsetting at 42 the lower end of bracket 4.

110 The coupler head is limited in its movement away from the bracket 4 and upheld in proper engaging position by the bars 29 115 and 32 and nuts 34 thereon which bear against the inner side of bracket 4, such nuts also serving to adjust the tension of the springs 40 which latter, should the coupler head be shifted out of proper line, return 120 it to the true engaging position. The flat bearing surfaces provided for nuts 34 enable the latter to steady the coupler head and positively set same in its true position, this action being supplemented by the head 125 12^b of the compression sleeve nut 12^a upon shank 11 and particularly owing to the above mentioned large bearing surface of such head exposed to the bracket. This position of nut 12^a upon shank 11 is varied in 130

accordance with any adjustment of nuts 34 that may be made and the engagement of the head 12^b with the bracket 4 insured.

The uncoupled position is shown particularly in Figs. 1 and 4, the former view illustrating particularly the position of the bearing frame 12 in advance of the bearing surfaces of the draw bar to insure positive and efficient engagement of the train pipe 10 coupler, this position being readily adjusted according to requirements by loosening bolts 8 so that the bracket 4, carrying the coupler head, can be shifted, the bolts moving in slot 6.

15 When the coupler heads of adjacent cars engage, see Fig. 5, they are moved back against the yielding resistance of springs 40, the loose connections of shanks 11 and bars 29 and 32 with brackets 4 enabling such 20 bars and shanks to move backward with the coupler heads. The tension of the compressed springs holds the bearing frames 12 tightly together and the mentioned loose connections of shanks and bars and the provision 25 of the roller sleeves upon the bars accommodating the lateral shifting of the coupler head incident to the rounding of curves by the cars and without impairing the tight connection of the bearing frames. 30 The engaging bearing frames 12 are positively locked together by means of hooks 44 respectively carried by the frames and at different sides thereof. When the frames engage the hook of each is adapted to be 35 automatically hooked over the other frame and likewise be automatically released prior to the disengagement of the frames.

Each hook is pivoted to its frame between a pair of spaced lugs 45 formed just at the 40 rear of the outer side of the pyramidal guide and is also pivotally connected at 46 to the outer end of a rod 46^a disposed longitudinally of the car and which extends inwardly at the side of shank 11 and passes 45 loosely through a perforated lug 47 projecting laterally from the bracket 4, the rod being screw-threaded at its inner end to receive a nut 48 which bears against the inner side of the perforated lug and restricts 50 the outward movement of the rod.

At a suitable distance along the rod and between the frame 12 and bracket 4 is formed a shoulder 49 which constitutes an abutment for a coiled spring 50 encircling 55 the rod and bearing between the bracket 4 and shoulder 49. The nut 48 serves as a means for adjusting the tension of spring 50.

When the coupler is disengaged from that of another car the hook 44 is out of engaging 60 position behind the pyramidal guide and as the two couplers meet and are forced back against springs 40 and the tension of the latter is increased the tension of springs 50 is also increased by the rearward movement of the rods 46^a with the coupler heads,

such springs 50 yieldingly retarding the rearward movement of rods 46^a each of which thus causes the hook connected thereto to swing outwardly through the outer apertured side of the pyramidal guide of 70 the frame to which it is pivoted and hook over the other frame. In this way the engaging frames are automatically locked together at both sides and as the frames disengage the outward movement thereof under 75 the recoil of springs 40 enables the rods 46^a to move forward and so causes the hooks to swing inwardly from engaging position and thus automatically release the frames and enable them to be drawn apart. 80

It will be apparent from the above that the tension of springs 40 and 50 is only increased when the coupler heads are together and that therefore excessive strain on such springs is avoided when the couplers are not 85 connected.

What I claim is as follows:

1. In a train pipe coupler, a coupler head having an outwardly projecting inclined guide at one side and an opening at the 90 other side, such inclined guide having a recess formed therein at the side adjacent the opening and the coupler head having a train pipe aperture located partially within said recess. 95

2. In a train pipe coupler, a coupler head having a train pipe aperture therein and being formed with a projecting inclined guide at one side of the aperture and an opening at the other side of the aperture, 100 such inclined guide flanking the top and bottom of the aperture and being recessed at one side of the latter.

3. In a train pipe coupler, a bracket, a coupler head, a shank extending from the 105 coupler head and passing through the bracket, and springs bearing between the bracket and coupler head, such springs being inclined away from the shank.

4. In a train pipe coupler, a bracket, a 110 coupler head, a shank extending from the coupler head and passing through the bracket, coil springs bearing between and inclined with relation to the bracket and coupler, and abutments for the springs presented by the bracket and coupler and disposed perpendicular to the axial line of the springs. 115

5. In a train pipe coupling, a bracket, a coupler head supported by the bracket, a 120 shank extending from the coupler head and passing through the bracket and a compression sleeve nut upon the end of the shank and adapted to bear against the side of the bracket opposite to that upon which the 125 coupler head is located.

6. In a train pipe coupling, a bracket, a coupler head supported by the bracket, a shank extending inwardly from the coupler head and passing through the bracket, a 130

sleeve nut screwed upon the end of the shank adjacent the inner side of the bracket, the sleeve portion of such nut being tapered from the head thereof and longitudinally split and a lock nut screwed upon the tapered sleeve.

7. In a train pipe coupling, a bracket, a coupler head supported by the bracket, a shank extending inwardly from the coupler head and passing through the bracket, bars extending from the coupler head and passing through the bracket, springs bearing between the coupler head and bracket and adapted to force the coupler head away from the latter, adjustable means upon each of the bars and shank, adapted to engage with the bracket and adjustably and uniformly limit the movement of the coupler head away from the bracket.

20. 8. In a train pipe coupling, a bracket having top and bottom openings therein, a coupler head disposed at the front of the bracket, upper and lower bars pivoted to the coupler, diverging from the latter and respectively 25 passing through one of said openings, sleeve nuts screwed upon the ends of said bars, the heads of such nuts being located at the rear of the bracket and the sleeve portions extending loosely through the openings and 30 being tapered adjacent the heads, a rocker sleeve encircling the sleeve portion of each sleeve nut and having that end adjacent the bracket rounded, coiled springs encircling the bars and bearing between the bracket 35 and the rocker sleeves, back and front bosses encircling the top opening, the tops of such bosses being inclined with respect to the bracket and the portion of the bracket adjacent the lower opening being forwardly 40 offset to provide bearing surfaces, for the

heads of the sleeve nuts and the rocker sleeves, perpendicular to the axial lines of their respective springs.

9. In a railway car, a support attached to the car and slotted in the longitudinal line of the latter, a train pipe coupling, a bracket for carrying such coupling and having a bifurcated upper end the arms of which are disposed on opposite sides of the support, a bolt passed through the upper 45 arms of the bracket and located in the slot of the support and lugs upon the inner sides of the upper arms of the bracket, such lugs adapted to engage with the underside of said support.

10. In a train pipe coupler, a coupler head formed with a train pipe aperture and having a projecting guide at one side of the train pipe aperture and an opening at the other side of such aperture, the side of the 60 guide adjacent the aperture being inclined and recessed about the latter and the wall of the recess being substantially parallel to the axial line of the train pipe aperture.

11. In a train pipe coupling, a coupler head formed with a train pipe aperture and having a projecting guide at one side of the train pipe aperture and an opening at the other side of such aperture, the side of the 65 guide adjacent the aperture being inclined and recessed and the wall of the recess extending outwardly from the head and being 70 curved about the train pipe aperture.

In testimony whereof, I have signed my name to this specification, in the presence 75 of two subscribing witnesses.

MARTIN ALLEN BARBER.
